UNITED STATES PATENT OFFICE.

CHARLES E. PETERSON, OF MINNEAPOLIS, MINNESOTA, ASSIGNOR OF ONE-HALF TO MERCHANT & KILGORE, OF MINNEAPOLIS, MINNESOTA, A CORPORATION OF MINNESOTA.

PENCIL.

Application filed October 23, 1924. Serial No. 745,507.

My invention provides an extremely simple and highly efficient pencil of the type that utilize and feed thin leads, and, generally stated, the invention consists of the 5 novel construction, combinations and arrangements of parts hereinafter described and defined in the claims.

The casing or body of the pencil may be made of any suitable material, but the general character of the pencil is such that it is especially adapted to use of a wooden casing or body of the same or general character as that of an ordinary lead pencil, which may be equipped with the customary 15 rubber.

In the accompanying drawings, which illustrate the invention, like characters indicate like parts throughout the several views.

20 Referring to the drawings:—

Fig. 1 is a view chiefly in axial section but with some parts shown in full and with some parts broken away, showing the improved pencil;

25 Fig. 2 is a transverse section on the line 2—2 of Fig. 1;

Fig. 3 is a transverse section on the line 3—3 of Fig. 1;

30 Fig. 4 is a transverse section on the line 4—4 of Fig. 1; and

Fig. 5 is a plan view showing the feed tube and its head removed from the casing or body of the pencil and detached from the feed stem.

35 The wooden casing or body 6 of the pencil is preferably made of two half sections glued together, as is done in the manufacture of an ordinary lead pencil; but this wooden casing or body is provided with a 40 quite large axial passage that preferably extends completely through the same. The said passage comprises a cylindrical portion 7 having diametrically opposite extension

45 grooves 8, which latter are preferably located 90° from the joint between the two wooden body sections, as best shown in Fig. 3.

To the butt end of the pencil body is or may be attached the customary rubber-holding ferrule 9 equipped with an ordinary rubber 10, which latter closes the butt end passage 7—8.

For holding one of the small marking leads y in position for use, there is provided a small metallic feed tube 11 that frictionally fits the cylindrical portion 7 of

the axial passage formed in the casing or wooden body. To the outer end of this feed tube 11 is rigidly secured, by sweating or other suitable means, an enlarged metallic feed head 12, which has an axial passage 13 for the lead y . The outer portion of this head 12 is tapered or conical and is diametrically split, preferably by two slits 14 that divide the tapered split portion into four spring prongs. The lead passage 13 at the 60 tips of these spring prongs will frictionally hold the lead against accidental outward movements, as best shown in Fig. 1. The rear or largest portion of the head 12 is 65 preferably substantially the diameter of the exterior of the casing or pencil body and is 70 preferably knurled so that the said head may be easily rotated.

Working within the feed table 11 is a feed stem or screw 15 that has threaded engagement with the inner end portion of said tube, the latter being preferably somewhat contracted to better afford the said threaded engagement. The rear or outer end of the feed stem 15 is bent, flattened or otherwise 80 formed so that it will slide in the grooves 8 but will hold said feed stem against rotation. In the construction illustrated, the said rear end of the stem 15 is formed with a U-shaped bend 16, the bow of which works in one of the grooves 8 and the long free 85 end of which works in the other of said grooves. Extra leads y^1 are adapted to be contained within the butt end of the casing or body 6, and to prevent these from dropping 90 downward when the pencil is in use, the long arm of the U-shaped bend 16 is flattened or widened at 16° so that it somewhat closely fills the cylindrical portion 7 of the 95 passage formed within the casing, see particularly Figs. 1 and 2.

The feed tube 11 has frictional engagement with the cylindrical portion 7 of the axial passage of the casing and, hence, is capable of rotation or of axial removal. To 100 better insure the proper frictional contact and to perform another and highly important function presently to be noted, the feed tube 11 is split at 11°, see particularly Fig. 5, from its inner end wall up toward its head. This splits the tube and permits the tube sections to be spread or sprung apart so that it will have to be pressed together for insertion into the cylindrical surface 7. Hence, when the split tube is inserted as 105 110

stated it will maintain proper frictional contact with said cylindrical surface 7; but more important than this, it splits the threaded end of said tube so that when the 5 tube 11, with the feed stem 15, is drawn out of the casing, said stem 15 may be freely removed or inserted into the tube so as to quickly set the same in proper position for feeding action either on a newly inserted 10 or on an old and shorter lead contained within the feed tube 11 and feed head. This enables the leads always to be inserted into the feed tube from the rear or split end and does not require the lead to be 15 forced back through the prongs of the feed head.

When the lead is properly applied in the feed tube and head and the feed stem is set in the proper initial position and the 20 tube is then reinserted into the casing with the head bearing against the end of said casing, a progressive feeding action of the lead may be produced simply by applying the finger and thumb to the knurled portion of the head 12, thereby rotating the same and the tube 11, causing the latter to act as a nut on the non-rotary feed stem 15. Of course, when the split feed tube is 25 inserted into the cylindrical surface 7, the threads of its inner end will be held in close contact with the threads of said feed stem 15. This pencil, as is obvious, is capable of being quickly refilled with lead and 30 re-adjusted for use. It is of such construction that it may be very cheaply made and, at the same time, will afford a highly efficient pencil. The fact that it is so well 35 adapted for use in connection with a wooden casing or body is in itself highly important, 40 for it is a well known fact that a wooden casing has a better feeling in the hand than a casing or body made of metal, celluloid,

or any other material, and moreover, on a wooden body, advertising matter or other words or designs may be very readily applied by stamping, printing or otherwise.

What I claim is:—

1. A pencil comprising a casing, a feed tube rotatively mounted and detachably seated in said casing and provided with a head abutting the writing end of said casing, said head affording an extended guide for the lead and means for rotating said feed tube, a feed stem having threaded engagement with said tube, itself slidably 55 and removably seated in said casing but held against rotation therein, the threaded portion of said feed tube being split so that when removed from said casing said stem may be slid axially through said split 60 threaded portion, the said casing, when said feed tube is inserted therein, serving to hold the split threaded portion of said feed tube engaged with the threads of said feed stem.

2. The structure defined in claim 1 in 65 which the split portion of said feed tube is under spring tension to spread when removed from said casing.

3. A pencil comprising a casing, a feed tube rotatively mounted and detachably 70 seated in said casing and provided with a feed head abutting the writing end of said casing, said head affording an extended guide for the lead and a means for rotating said feed tube, and a feed stem having 75 threaded engagement with said feed tube, itself removably seated in said casing but held against rotation, said casing at the rear of said feed stem being formed with a lead-holding chamber, the rear end of said feed 80 screw being formed to close the front end of said lead-holding chamber.

In testimony whereof I affix my signature.
CHARLES E. PETERSON.
